CLAIM

The ornamental design for a bag rack, as shown and described.

DESCRIPTION

FIG. 1 is an enlarged front elevational view of a single clip mounted on a strap, being one of a plurality of identical clips used in our bag rack design as described below;

FIG. 2 is an enlarged bottom plan view of the design of this invention;

FIG. 3 is an enlarged front perspective view of a single clip mounted on a strap;

FIG. 4 is an enlarged top plan view of the design of this invention;

FIG. 5 is an enlarged rear elevational view of a single clip mounted on a strap;

FIG. 6 is an enlarged left side view of a single clip mounted on a strap;

FIG. 7A is a front perspective view of the lowest section of six continuous sections of the bag rack showing our new design;

FIG. 7B is a front perspective view of the next higher section being a continuation of the section of FIG. 7A;

FIG. 7C is a front perspective view of the next higher section being a continuation of the section of FIG. 7B;

FIG. 7D is a front perspective view of the next higher section being a continuation of the section of FIG. 7C;

FIG. 7E is a front perspective view of the next higher section being a continuation of the section of FIG. 7D;

FIG. 7F is a front perspective view of the highest section being a continuation of the section of FIG. 7E;

FIG. 8A is a rear perspective view of the lowest section of six continuous sections of the bag rack showing our new design;

FIG. 8B is a rear perspective view of the next higher section being a continuation of the section of FIG. 7A;

FIG. 8C is a rear perspective view of the next higher section being a continuation of the section of FIG. 7B;

FIG. 8D is a rear perspective view of the next higher section being a continuation of the section of FIG. 7C;

FIG. 8E is a rear perspective view of the next higher section being a continuation of the section of FIG. 7D; and,

FIG. 8F is a rear perspective view of the highest section being a continuation of the section of FIG. 7E.
